Primary Examiner — Mary Ann Calabrese*Assistant Examiner* — Katelin G Kloberg(57) **CLAIM**

The ornamental design for a bedside table set, as shown and described.

DESCRIPTION

FIG. 1 is a perspective view of a bedside table set, showing my new design in a nested configuration;

FIG. 2 is a front view thereof;

FIG. 3 is a front view of a bedside table set, showing my new design in an un-nested configuration;

FIG. 4 is a back view of the bedside table set as shown in FIG. 1;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate the portions of the bedside table set that form no part of the claimed design.
